UNITED STATES PATENT OFFICE.

LOUIS SMITH, OF CHICAGO, ILLINOIS, ASSIGNOR OF ONE-HALF TO
CHARLES A. ARMBRUSTER, OF CHICAGO, ILLINOIS.

DEVICE FOR PREVENTING FRAUDULENT RAISING OF CHECKS, &c.

SPECIFICATION forming part of Letters Patent No. 773,817, dated November 1, 1904.

Application filed August 20, 1903. Serial No. 170,106. (No model.)

To all whom it may concern:

Be it known that I, LOUIS SMITH, of Chicago, in the county of Cook and State of Illinois, have invented certain new and useful Improvements in Devices for Preventing Fraudulent Raising of Checks, &c.; and I do hereby declare that the following is a full, clear, and exact description thereof, reference being had to the accompanying drawings, and to the letters of reference marked thereon, which form a part of this specification.

This invention relates to certain new and useful improvements in devices for preventing the fraudulent raising of checks, drafts, and like documents of that class designed to impress upon or perforate in the document numbers or characters corresponding with the value represented by the check or other document.

My invention contemplates the use of a plurality of character disks or wheels located side by side and independently rotatable on a common axis, as a shaft, and provided on their peripheries with a plurality of number and character types which are designed to be severally brought to a common printing-line by rotation of the disks on their axes and a reciprocating plunger or equivalent device which presses the check or other document

upon said number or character types, and thereby produce on the document a certain combination of numbers and characters which have been set up by suitable manipulation of the character-disks. Preferably the character-disks are provided with levers or indicators which coöperate with scales on the frame of the machine embracing characters and numbers corresponding with the arrangement of the numbers and characters on the

peripheries of the disks, thereby facilitating the setting up of the desired combinations, and means are provided for locking said levers or indicators in their various positions, so as to maintain intact a given combination after it has once been set up and until an impression has been taken therefrom. The number and character types may be arranged to produce an embossed impression, may operate in connection with an inking-ribbon to

produce an inked impression on the document, or may be constructed to perforate the document in the manner of the well-known check-perforator.

As shown in the drawings, Figure 1 is a front elevation of a device made in accordance with my invention. Fig. 2 is a vertical section thereof, taken on line 2 2 of Fig. 3. Fig. 3 is a vertical section taken on line 3 3 of Fig. 2. Fig. 4 is a horizontal section taken on line 4 4 of Fig. 3. Fig. 5 illustrates the printing periphery of one of the character-wheels, being shown as it would appear if straightened.

As shown in the drawings, A designates the base of the machine, which is made of suitable weight and width to give stability to the machine.

B B designate two side frame-plates attached by screws or the like to the base, and C designates a curved inclosing frame-plate which incloses the character-disks and is attached to the base-plate at the front and rear of the device by means of screws e, as more clearly shown in Figs. 1 and 3. D designates a horizontal stationary shaft extending between and affixed at its ends in apertures in said side plates B. Said side plates are provided with inwardly-extending bosses to give suitable width of bearing to the shaft. The side plates are provided in a portion of their margins with rabbets which receive the margins of the curved inclosing plate, as shown in Fig. 2, and the ends of the shaft extend through the end plates and are provided with nuts d, by which said end plates are clamped against said curved inclosing plate, whereby the parts are held firmly together. The ends of said shafts are reduced to provide outwardly-facing shoulders against which the nuts d bear.

E designates a plurality of character disks or wheels which are arranged side by side and are independently rotative on the shaft D. Said disks are separated by means of washers e, which avoid friction between the adjacent faces of the disks and are provided on their peripheries with number or character types, as shown in Figs. 2, 3, and 4. Each of said

disks is provided with twelve types, as herein shown, one appropriated to each of the nine digits, one appropriated to a suitable character which is adapted to be imprinted at the end of a combination of numbers, and one of which is blank. The inclosing curved frame-plate C is provided centrally at the top of the device with a transverse opening parallel with the shaft D, through which the tops of the disks project sufficiently for the check or other document to be brought into proper printing contact with said type, and it is at this part of the device that the printing-line is formed or set up. The inclosing frame-plate C is provided at its top at the left-hand side of the printing-line with a suitable character c^3 , representing the dollar-sign, (\$), as more clearly shown in Fig. 4. As many character-disks E are employed as are necessary to produce a number having the required number of numerals and characters, and such number of wheels will vary in different uses of the device. Six are herein shown, upon which a number having five numerals therein may be set up, one disk being reserved to print at the end of the number the stop or terminating character shown at the lower end of the plan of one of the disk peripheries in Fig. 5 and shown at the right hand of the set-up number in Fig. 4.

Each of the character-disks is shown as provided with a rigidly-attached lever or indicator E', and said levers or indicators project forwardly through slots c^2 in the curved front face of the inclosing frame C, as more clearly shown in Figs. 1 and 4. At the side of each slot is a series of numbers and characters corresponding to the numbers and characters on the disk peripheries, said series constituting scales which coöperate with the levers or indicators to guide the person using the device in setting up the proper combination of numbers and characters. The slots are provided in lateral alinement with said numbers or characters with a plurality of laterally-directed notches c^2 , which are adapted to severally receive the levers or indicators E' and constitute stops by which said levers and their disks are held from movement in both directions in any position in which they are set. The arrangement of the series of numbers and characters constituting said scales is shown at the side of the left-hand slot of the inclosing frame of the machine in Fig. 1, and by a comparison of said scale with Fig. 5 it will be seen that it corresponds exactly with the series of numbers or characters on the peripheries of the disks. By preference the blank types on the disks are arranged at the centers of the disk peripheries with the numbers and characters apportioned on each side thereof as nearly as may be, while the blanks and numbers and characters of the scales bear a similar relation. With this arrangement of the numbers and characters of the scales and

disks when the levers or indicators occupy their horizontal positions, as shown in Fig. 1, they are in lateral alinement with the blank spaces on the scales, and from the foregoing description it will be readily understood that the blank types on the disk are at this time set up in the printing-line, so that if an impression be made at this time no numbers or characters will appear, but only the dollar-sign (\$) at the left-hand side of the printing-line. When a combination of numbers or characters are to be set up, the several levers are moved in their slots, each one opposite to the number or character on its associated scale which accords with the number or character of the attached disk, which should appear in the printing-line. The levers or indicators are given a tendency to spring into the notches c^2 at the sides of their slots, so as to be automatically locked when moved in lateral alinement with said notches. When the disks are to be manipulated to set up a given combination, said levers are sprung out of their notches which they then occupy, and are thereafter swung upwardly or downwardly into line with the proper numbers or characters on the scales and released and are by their own resiliency sprung into the proper holding-notch c^2 . In this manner the disks are held securely in proper position after a combination has been set up.

In Fig. 4 a combination of numbers or characters are shown as set up on the printing-line, so that in said figure the levers or indicators E' occupy different positions from those shown in Figs. 1 and 2. The dotted lines indicating the levers or indicators shown in Fig. 2 show the maximum swing of the levers necessary to rotate the disks from their central positions to the limits of their movements in each direction.

Any suitable form of plunger or stamp may be employed to press the check or other document upon the line of type at the printing-line to produce the impression desired on the check.

As herein shown, F designates a vertically-reciprocating plunger which reciprocates in a guide-head G, located above the printing-line and formed on the forward end of a forwardly-curved shank G', rising from the rear side of the base of the machine, as more clearly shown in Fig. 3. A lever H, hinged in said head and provided with a cam or eccentric H', serves to depress said plunger, and the plunger may be retracted by a suitably-applied spring when pressure on said lever is released. The plunger and the plunger-actuating mechanism shown is substantially the same as the well-known form of seal-stamp and need not be further described. The plunger is provided on its lower end with a flat horizontal plunger plate or platen F', made of suitable width and of a length sufficient to extend over the entire length of the maximum printing-

- line, so as to produce an equal pressure on all the type which may be at any time set up on the printing-line. As before stated, said type may be formed to perforate the check or other document, may be made to emboss the same, or may be arranged to produce an inked impression thereon. The device herein shown is arranged to produce a combined inked and embossed impression. For this purpose an inking-ribbon I is provided, which is trained beneath said horizontal platen and is wound at its ends on two spools or reels I' I', rotatively mounted in suitable bearings i, rising from the ends of said plate. No automatic shifting mechanism is herein shown to feed said ribbon along said platen, but such mechanism may be provided, if desired. In order to produce an embossing effect on the check or other document, the bottom of the platen is provided with a yielding pad J, and as a result of this construction when the platen is pressed upon a set-up line of type it strikes it with a yielding pressure and produces not only an inked impression, but causes the type to be forced upwardly into the check or other document, thereby producing the embossed effect. If the ribbon be omitted, the remaining construction will operate to produce the embossed effect.
- 30 A horizontally-movable gage-plate K is affixed to a suitable horizontal flange c' at the top of the inclosing frame C, and said plate has slotted connection with said flange, as shown in Figs. 3 and 4, and is provided at its forward margin with a vertical gage-flange k' which is adapted to be engaged by the margin of the check when placed in the machine to be impressed, whereby may be insured the stamping of the checks at uniform distances from the margins thereof. By adjustment of said gage-plate the impressions may be made at varying distances from the margins of the checks.
- 35 Preferably the numeral-types of the character-disks are formed to provide spaces not only for the numerals, but are also made sufficiently large to receive thereon the word corresponding with said numeral. This arrangement is preferred in order to make the falsification of a number imprinted on a check or other document more difficult, as it is obvious that more skill is required to change both the numeral and word than would be required to change the numeral alone.
- 40 The operation of the device is obvious from the foregoing, but may be briefly recapitulated as follows: When a check or other document is to be stamped or impressed, the number and character wheels are manipulated to set up or bring to the printing-line the numbers and characters to constitute the combination required, and such manipulation of the disks is effected by grasping the levers or indicators E', swinging them out of their notches c', and moving them upwardly or
- 45 downwardly, as required, in their slots and thereafter allowing said levers to spring into other notches opposite to the figures or characters of the scale which correspond with those which are to appear in the printing-line. In setting up the number in Fig. 4 the left-hand lever is shifted downwardly from its central position to six, (6,) the second lever is shifted upwardly to one, (1,) the third lever is shifted downwardly to six, (6,) the fourth lever is shifted upwardly to two, (2,) the fifth lever is shifted upwardly to the stop or terminating character, and the last lever remains in its horizontal position, so as to leave the blank space of its attached disk in the printing-line. The check or other document is then placed between the type-line and the plunger, and thereafter said plunger is depressed by swinging the lever H downwardly in a familiar manner. In this manner the check is forced against the type, and an impression is made on the face of said check corresponding with the numbers set up in the printing-line.
- 50 The machine herein shown and described is very compact in its arrangement and construction, and the character-disks are readily manipulated to set up the proper combination at the printing-line. When once set up, the disks are held firmly in place until again shifted for setting up a new combination. After a given combination has been set up and a number of checks are to be printed with the number represented by said combination it will be obvious that this may be accomplished without changing the combination, so that when this occurs such work may be performed very rapidly. As herein shown, only the numerals of the number representing the dollar of the check or other document to be impressed is provided for, although the numbers representing the cents value may be added, if desired.
- 55 It is obvious that changes may be made in the structural details of the device without departing from the spirit of the invention, and I do not wish to be limited to the specific combination herein illustrated, excepting as herein made the subject of specific claims.
- 60 I claim as my invention—
1. A check-stamping device comprising a frame, a shaft extending across the frame and fixed at its ends in the side walls thereof, a plurality of character-disks mounted directly upon said shaft side by side and independently rotatable, each provided on its periphery with a series of character-types, said frame being provided in its top wall with a transverse opening through which the types of the disks project to constitute the printing-line, and in its front wall with a plurality of slots, one in substantial alinement with each type-disk, levers fixed directly to said disks and extending forwardly through said slots and a platen for pressing the work against the types.

2. A check-stamping device comprising a frame, a shaft extending across said frame and fixed at its ends in the side walls thereof, a plurality of character-disks mounted directly upon said shaft side by side and independently rotatable, each provided on its periphery with a series of character-types, said frame being provided in its top wall with a transverse opening through which the types of the disks project to constitute the printing-line and in its front wall with a plurality of slots, each in substantial alinement with one of the type-disks, levers affixed directly to said disks and extending forwardly through said slots, means for separately locking said disks in place, and a platen for pressing the work against the types.
3. A check-stamping device comprising a frame, a shaft extending across the frame and fixed at its ends in the side walls thereof, a plurality of character-disks mounted directly upon said shaft, side by side and independently rotatable, each provided on its periphery with a series of character-types, said frame being provided in its top wall with a transverse opening through which the types of the disks project to constitute the printing-line and in its front wall with a plurality of slots, each in substantial alinement with one of the type-disks, levers fixed directly to said disks, and extending forwardly through said slots, a scale on the front wall of said frame adjacent to the slots having a series of characters corresponding in relative position to the character-types of the disks, and a platen for pressing the work against the types.
4. A check-stamping device comprising a frame, a shaft extending across the frame and fixed at its ends in the side walls thereof, a plurality of character-disks mounted directly upon said shaft side by side, and separated by thin plates or washers, said disks being independently rotatable on said shaft and each of the disks being provided on its periphery with a series of character-types, said frame being provided at its top with a transverse opening through which the types of the disks project to constitute the printing-line, and in its front wall with a plurality of slots, each in substantial alinement with one of the type-disks and levers fixed directly to said disks and extending forwardly through said slots, said slots being provided at their sides with notches adapted to receive the levers to lock the latter in place, and a platen for pressing the work against the types.
5. A check-stamping device comprising a frame consisting of a base, end plates attached thereto and a curved inclosing plate between said end plates and attached to the base, a shaft extending between and attached at its ends to said end plates, a plurality of character-disks located side by side and independently rotatable on said shaft, and provided on their peripheries with a series of character-types, said curved inclosing plate being provided at its top with a transverse slot through which the character-types project to constitute the printing-line, levers attached to said disks and extending forwardly through slots in the front part of said inclosing plate which are severally in substantial alinement with said disks, said slots being provided with laterally-directed notches adapted to severally receive the levers, a scale on the said frame having characters located in lateral alinement with said notches and corresponding in kind and relative positions to the character-types of the disks, and a platen for pressing the check or the like upon the types presented or set up at the printing-line.
6. A check-stamping device comprising a frame, a shaft therein, a plurality of character-disks mounted side by side upon said shaft and independently rotative thereon, each provided on its periphery with a series of character-type, said frame being provided in its top with a transverse opening through which the types of the disks project to constitute the printing-line and in its front wall with a plurality of slots, levers affixed directly to the side faces of said disks and extending forwardly through said slots and a platen for pressing the work against the types.

In testimony that I claim the foregoing as my invention I affix my signature, in presence of two witnesses, this 17th day of August, A.D. 1903.

LOUIS SMITH.
